TOY TELEPHONE

Filed Jan. 21, 1930

UNITED STATES PATENT OFFICE

NORMAN W. HILL, OF EAST HAMPTON, CONNECTICUT, ASSIGNOR TO THE N. N. HILL
BRASS COMPANY, OF EAST HAMPTON, CONNECTICUT, A CORPORATION

TOY TELEPHONE

Application filed January 21, 1930. Serial No. 422,316.

This invention relates to an improvement in toy telephones. The object of the invention is to provide a toy telephone simulating the hand set or "continental" style of combined transmitter and receiver, with a vertically-movable standard, the movement of which is adapted to operate an audible signal. A further object of this invention is to combine with such a telephone set a dial mechanism simulating the dial mechanism now coming into use in actual desk sets, and the invention consists in the construction as hereinafter described and particularly recited in the claims.

15 In the accompanying drawings:

Fig. 1 is a front view of a toy telephone constructed in accordance with my invention;

Fig. 2 is a side view of the same;

20 Fig. 3 is an underside view thereof;

Fig. 4 is a sectional view on the line 4—4 of Fig. 1; and

Fig. 5 is a sectional view on the line 5—5 of Fig. 4.

25 In carrying out my invention, I employ a base 10 provided with a hollow post 11 into which extends the stem 12 of a yoke 13 adapted to receive a hand set 14 simulating the usual telephone hand sets and provided at 30 one end with the simulation of a receiver 15 and at the opposite end with the simulation of a transmitter 16. The stem 12 is provided with a pin 17 extending outwardly through a slot 18 in the post 11 to engage with an operating-part 19 of a bell-mechanism 20, like an ordinary bicycle bell, which is attached to the post by means of a clip 21, so that when the yoke is depressed, the bell will be sounded.

35 It is obvious, without illustration, that the stem 12 might extend outside the post 11, and it is also obvious, without further illustration, that the bell 20 might be replaced by any audible signal.

If the base is provided with a dial mechanism, the stem 12 will be provided at its lower end with a downwardly-extending pin 22 to engage with an inclined finger 23 at the inner end of a pawl 24 pivotally mounted on the underside of a plate 25 secured to the upper 40 face of the base 10, the nose 26 of the pawl

extending in the path of a ratchet 27 fixed to a shaft 28 mounted in a bearing 29 fixed to the plate 25, the shaft being reduced at its outer end for the reception of a perforated signal-plate 30 which is fixed to the shaft by a nut 31. On the plate 25 is a disk 32 of paper or similar material upon which is placed numbers or letters which are exposed through openings 33 in the signal-plate 30. The plate 25 is also provided with a stud 34 adapted to be engaged by a lug 35 in the signal-plate 30.

55 The pawl 26 is normally held in engagement with the ratchet 27 by a spring 36, and around the shaft 28 is a coil-spring 37, one end of which is fixed to the shaft and the other end to the plate 25 so that, as the signal-plate is turned, additional tension will be applied to the spring.

60 In use, the child manipulates the signal-disk and then presses down upon the hand set before removing it from the yoke. This downward movement of the yoke sounds the signal, as before described, and a downward movement of the yoke forces the pin 22 into engagement with the finger 23 of the pawl 24, so as to move the pawl out of engagement with the ratchet, so as to permit the spring to return the signal-disk to its normal position, by which it is stopped by the engagement of the lug 35 with the stud 34, which also acts to prevent the signal-plate from being turned more than one complete revolution.

65 I thus provide a very attractive toy for children simulating a hand set telephone and which may also be provided with a simulation of the disk signaling system now coming into vogue.

70 I claim:

1. A toy telephone comprising a base, a post mounted thereon, a yoke provided with a stem telescopically connected with said post, an audible signal, and means operated by the yoke for sounding the said signal.

75 2. A toy telephone comprising a base, a tubular post mounted thereon, a yoke provided with a stem entering said post, a signal secured to said post, and means operated

by the downward movement of said stem to sound the said signal.

3. A toy telephone comprising a base, a post mounted thereon, a yoke formed with a stem telescopically connected with said post, said stem provided at its lower end with a downwardly-projecting pin, a signal secured to said post and adapted to be operated by the downward movement of said

10 stem, a disk mounted on said base, a shaft mounted in said disk, a ratchet mounted on said shaft, a pawl pivotally connected with said plate and engaging said ratchet and extending rearward in position to be engaged by said pin, a perforated signal-disk connected with said shaft, and a spring normally acting to move said disk when the pawl is released.

4. A toy telephone comprising a base, a post mounted thereon, a yoke formed with a stem telescopically connected with said post, said stem provided at its lower end with a downwardly-projecting pin, a signal secured to said post and adapted to be operated by the downward movement of said stem, a disk mounted on said base, a shaft mounted in said disk, a ratchet mounted on said shaft, a pawl pivotally connected with said plate and engaging said ratchet and extending rearward in position to be engaged by said pin, a perforated signal-disk connected with said shaft, and a spring normally acting to move said disk when the pawl is released, the said plate and signal-disk provided with co-acting stops, whereby the movement of the disk is limited.

5. In a toy telephone, the combination with a manually-rotatable dial; spring-means normally exerting an effort to turn the said dial in one direction; and a manually-releasable latching device for releasably holding the said dial in a given position of manual adjustment.

6. In a toy telephone, the combination with a manually-rotatable dial; spring-means normally exerting an effort to turn the said dial in one direction; a latching device for releasably holding the said dial in a given position of manual adjustment; and manually-operable means for moving the said latching device to release the said dial to the action of the said spring-means.

7. In a toy telephone, the combination with a manually-rotatable dial; spring-means normally exerting an effort to turn the said dial in one direction; a latching device for releasably holding the said dial in a given position of manual adjustment; and a receiver-holder operatively connected to the said latching device for moving the same into position to release the said dial to the action of the said spring-means.

8. A toy telephone comprising a base, a post mounted thereon, a receiver-holder mounted on the post, a signal mounted on

the said holder and adapted to be operated by the movement of the receiver-holder, a dial-mechanism mounted on the base, including a dial and a reversing spring therefor, and means operated by the receiver-holder for releasing the said dial to the reversing action of the said spring.

In testimony whereof, I have signed this specification.

NORMAN W. HILL.
